John Howard McElroy,
HIS ATT'Y.

UNITED STATES PATENT OFFICE.

JOHN HOLLAND-LETZ, OF CROWN POINT, INDIANA, ASSIGNOR TO THE LETZ MANUFACTURING COMPANY, OF CROWN POINT, INDIANA, A CORPORATION OF INDIANA.

GRINDING BURR.

Application filed July 28, 1924. Serial No. 728,628.

To all whom it may concern:

Be it known that I, JOHN HOLLAND-LETZ, a citizen of the United States, and a resident of Crown Point, in the county of Lake and State of Indiana, have invented certain new and useful Improvements in Grinding Burrs, of which the following is a specification.

My invention is concerned with burrs for grinding mills, such as are used by farmers for grinding feed, and it is designed to produce a burr for coarse grinding that shall have a large capacity without requiring a great deal of power to drive it, and which shall be capable of grinding a wide variety of feeds, such as ear corn, oats, corn husks, soy beans, hay and alfalfa.

To illustrate my invention, I annex hereto a sheet of drawings, in which the same reference characters are used to designate identical parts in all the figures, of which,—

Fig. 1 is a plan view of a portion of a burr embodying my invention; and

Figs. 2, 3, 4 and 5 are views in section on the lines 2—2, 3—3, 4—4 and 5—5, respectively.

In carrying out my invention, I employ a generally annular casting A preferably provided on its rear face with a pair of annular ribs B and C and the apertures D for the bolts by which the burrs are secured in place.

The grinding face is formed of a series, preferably four, of similar or substantially identical sections, and one of said sections may be considered as extending from one of the tearing teeth E illustrated to the other one. The burr may be considered as made up of the base or body portion, having the narrow outer face portion F, which is substantially flat, with the inclined face portion G slanting downwardly therefrom to the open center. All of the teeth project upward from these surfaces F and G, and their flat grinding surfaces are all in the same plane, being formed by grinding off the tops of the teeth as they exist in the natural casting.

The tearing teeth E have their grinding surfaces extending practically laterally across the ring, and as a great strain is sometimes put on these teeth, I strengthen them by providing the generally triangular portion H back of them, which portion is not slanted off so sharply as the rest of the

base portion G to give them a greater backing of metal. The feeding teeth J also extend practically across the ring, and both they and the tearing and feeding teeth E extend at a substantial angle to a radial line through either the point or the heel of the teeth.

Associated with the inclined tearing and feeding teeth E and the feeding teeth J, are the four feeding teeth K, K', K² and K³, which are inclined to the radial lines passing through them even more than the teeth E and J, and which accordingly have a substantial feeding action although they do not extend entirely to the inner periphery of the ring. All these teeth K, K', K² and K³ have their outer portions inclined at an angle to their smaller, inner portions, and their ground-off, flat shearing and grinding surfaces include the angle between the inner and outer portions. Another group of interposed teeth L, L', L², L³, L⁴, L⁵, L⁶, L⁷, L⁸ and L⁹ may be called auxiliary feeding teeth, inasmuch as their pointed inner portions below their grinding surfaces have that function to some extent. Said inner portions are designed to accommodate themselves to the spaces between the main feeding teeth, and with said main feeding teeth to form channels through which the material may pass outward in a generally radial direction to the grinding teeth proper.

These grinding teeth proper are arranged in rows, consisting of the teeth M and M'; N, N' and N²; O, O', O² and O³, P, P', P², P³, P⁴, and P⁵; and Q, Q' and Q² to the right of the tearing teeth E; and of the teeth m and m'; n, n' and n²; o, o', o², o³, o⁴, o⁵; p, p', p², p³, p⁴ and p⁵; and q, q' and q² to the left of said teeth; and it will be noted that the grinding surfaces of the teeth L and K form a continuation of the m and m' series; the grinding surfaces of the teeth L', L² and K² form a continuation of the n, n' and n² series; the grinding surfaces of the teeth L³ form a continuation of the o, o', o², o³, o⁴ and o⁵ series; the grinding surfaces of the teeth L⁴ and K² form a continuation of the M and M' series; the grinding surfaces of the teeth L⁵, L⁶ and K³ form a continuation of the N, N' and N² series; and that the grinding surfaces of the teeth L⁷, L⁸ and L⁹ form a continuation of the O, O', O² and O³ series.

It will also be noted that the distances between the teeth that are in the same longi-

tudinal axial line, such as the teeth n and m , o and n^2 , p and o^2 , p' and o^3 , for instance, is almost as great as the length of the teeth, producing a faster feed than is possible 5 where the teeth are closer together, as has been the practice heretofore. It will also be noted that the teeth of the different series, such as o , o' , o^2 , o^3 , o^4 and o^5 , are staggered relative to the teeth of the adjacent series, 10 such as p , p' , p^2 , p^3 , p^4 and p^5 , thus requiring the material to travel in a zigzag path in getting to the outer periphery of the rings, and resulting in a more thorough grinding than if the material could pass outwardly in 15 straight lines.

It will further be noted that the axes of all the grinding teeth in each of the eight groups are parallel to each other and also to a radial line passing through the center 20 of each group. This results in these grinding teeth having on one side of the radial line a slight tendency to feed the material outward, while on the other side of said radial line a corresponding tendency to feed 25 it backward or inward exists, this alternating action producing an intermittent or wave-like action that clears the burrs better than a uniform outward movement.

The operation of a pair of these burrs 30 designed as above described can be seen from a study of the same. I have found by experience that for coarse grinding of a variety of feeding material, as above enumerated, these burrs have a large capacity, practically double that of those they superseded, and furthermore that they produce a minimum of flour, which is very objectionable when ground feeds are fed dry, as it tends 35 to get into the nostrils of the animals.

40 While I have shown and described my invention as embodied in the form which I at present consider best adapted to carry out its purposes, it will be understood that it is capable of some modifications, and that I do 45 not desire to be limited in the interpretation of the following claims except as may be necessitated by the state of the prior art.

What I claim as new, and desire to secure by Letters Patent of the United States, is:

50 1. In a grinding burr, the combination with an annular base, of a series of feeding teeth extending across the base at an angle to radial lines projected therethrough, and groups of grinding teeth, the axes of said 55 grinding teeth in each group being substantially parallel to each other and to a radial line projected through the center of the group and said grinding teeth being short and so located that they form tangential 60 lines of openings between the adjacent ends of the teeth.

65 2. In a grinding burr, the combination with an annular base, of a series of feeding teeth extending across the base at an angle to radial lines projected therethrough, and a

group of grinding teeth on the base, the axes of the grinding teeth in a group being substantially parallel to each other and to a radial line projected through the center of the group and said grinding teeth being 70 short and so located that they form tangential lines of openings between the adjacent ends of the teeth.

3. In a grinding burr, the combination with an annular base decreasing in thickness 75 toward the inner periphery of the same, of grinding teeth on the face of the base, and a plurality of tearing teeth projecting inwardly beyond the general outline of the inner periphery, each of said tearing teeth 80 having a backing in said base of greater thickness than the adjacent body of the base in advance of the teeth.

4. In a grinding burr, the combination with an annular base, of a plurality of feeding and tearing teeth extending entirely across the base and projecting inwardly beyond the general outlines of the inner periphery, a plurality of feeding teeth, all of 85 said teeth extending in the same general direction relative to radial lines projected therethrough, and grinding teeth located outside of the feeding teeth, substantially 90 as and for the purpose described.

5. In a grinding burr, the combination 95 with an annular base, of a plurality of feeding and tearing teeth extending entirely across the base and projecting inwardly beyond the general outlines of the inner periphery, a plurality of feeding teeth, all of 100 said teeth extending in the same general direction relative to radial lines projected therethrough, and groups of grinding teeth, the axes of said teeth in each group being substantially parallel to each other and to a radial line projected through the center 105 of the group.

6. In a grinding burr, the combination with an annular base, of a plurality of feeding and tearing teeth extending across the 110 base and projecting inwardly beyond the general outlines of the inner periphery, a plurality of feeding teeth, all of said teeth extending in the same general direction relative to radial lines projected therethrough, and groups of grinding teeth, the axes of said teeth in each group being substantially parallel to each other and to a radial line projected through the center of the group, some of said feeding teeth having 115 portions extending outwardly therefrom parallel to the axes of the grinding teeth of the adjacent groups.

7. In a grinding burr, the combination with an annular base, of a plurality of feeding and tearing teeth extending across the 120 base and projecting inwardly beyond the general outlines of the inner periphery, a plurality of feeding teeth, all of said teeth extending in the same general direction rela- 125 130

tive to radial lines projected therethrough, and grinding teeth located outside of the feeding teeth and arranged in rows in staggered relationship to adjacent rows, substantially as and for the purpose described.

8. In a grinding burr, the combination with an annular base, of a plurality of feeding and tearing teeth extending across the base and projecting inwardly beyond the general outlines of the inner periphery, a plurality of feeding teeth, all of said teeth

extending in the same general direction relative to radial lines projected therethrough, and grinding teeth located outside the feeding teeth and arranged in rows in staggered relationship to adjacent rows, the feeding teeth in some instances constituting continuations of the rows of grinding teeth, substantially as and for the purpose described. 15

In witness whereof, I have hereunto set 20
my hand.

JOHN HOLLAND-LETZ.
